SHREDDING APPARATUS

Francis M. Wick, Youngstown, Ohio

Application June 12, 1933. Serial No. 675,434

9 Claims. (Cl. 164—68)

The invention relates to apparatus for shredding sheet material, and more particularly to apparatus for shearing a pack of sheets of paper and the like into relatively long shreds or strips.

5 Prior constructions for shredding paper stock and the like have included a plurality of spaced cutting disks mounted on a rotary shaft, or a plurality of spaced intermeshing cutting disks mounted on parallel rotary shafts, the shaft or shafts being disposed at right angles to the direction of feed of the sheet pack, so that the paper is cut or torn longitudinally into strips.

With this type of construction, excessive power is required to force the plurality of cutting disks 15 simultaneously through the pack of sheets, so that the pack must be kept relatively thin and the capacity of the apparatus is relatively small.

In shredding paper for commercial use, it is desirable to produce various widths of shreds or strips to suit different purposes, and it is very difficult and impracticable to adapt such prior constructions for cutting different widths of strips, because the spacing of all of the cutting disks on the shaft must be adjusted accordingly.

25 Moreover, such prior constructions are heavy and cumbersome, as well as expensive to manufacture.

Accordingly, it is an object of the present invention to provide an improved apparatus for shredding paper and the like which requires a minimum 30 of power for operation.

Another object is to provide an improved shredding apparatus having increased capacity.

A further object is to provide an improved 35 shredding apparatus which may be easily adapted for producing various widths of strips of paper.

A still further object is to provide an improved shredding apparatus having means for shearing a pack of sheets transversely, with respect to its 40 direction of feed, into strips having a length equal to the full width of the pack.

And finally, it is an object of the present invention to provide improved apparatus for shredding paper and the like embodying the foregoing advantages, which apparatus is simple and light in 45 construction, and inexpensive to manufacture.

These and other objects are attained by the improvements comprising the present invention, which are described in detail in the following specification, and which are distinctly set forth in the 50 appended claims.

In general terms the present invention comprises shredding apparatus including a housing, means in the housing for shearing a pack of sheets 55 into strips each having a length equal to the width

of the pack, said shearing means including a cutter bar mounted in the housing, a rotatable knife mounting shaft journaled in the housing parallel with said cutter bar, a plurality of circumferentially and angularly arranged knives mounted on 60 the knife mounting shaft and cooperatively associated with the cutter bar for shearing strips from the pack, a deflecting plate mounted adjacent to each knife and spaced radially inward therefrom for deflecting the paper strips radially outward, 65 upper and lower feed rolls parallel with the cutter bar and adapted for feeding a pack of sheets onto the cutter bar at right angles thereto, means for rotating the knife mounting shaft, and gearing means operatively connecting said shaft to the 70 feed rolls for driving the feed rolls at equal speeds.

Referring to the accompanying drawings forming part hereof.

Figure 1 is a plan sectional view of the improved shredding apparatus, as on line 1—1, Fig. 2;

75

Fig. 2 is a side elevation thereof;

Fig. 3 is a longitudinal sectional view taken substantially on line 3—3, Fig. 1; and

Fig. 4 is an enlarged fragmentary view similar to Fig. 3, showing the arrangement of the knives 80 and deflecting means.

Similar numerals refer to similar parts throughout the drawings.

The improved shredding apparatus is indicated generally at 10 in Figs. 1, 2 and 3, and preferably 85 includes a base or supporting frame indicated at 11, and an enclosure frame or housing 12 carried on the base 11 and having the top wall 12a and the side walls 12b and 12c.

A knife mounting shaft 13 is journaled in the 90 side walls 12b and 12c of the housing 12, as by means of suitable bearings indicated at 14 in Fig. 1. The shaft 13 is preferably disposed horizontally and transversely of the shredding apparatus 10.

Means for mounting a series of circumferentially arranged knives upon the knife mounting shaft 13 preferably includes a pair of spiders or end heads indicated generally at 15 and 15'. The spiders 15 and 15' are spaced inwardly of the side walls 12b and 12c, respectively, of the housing 12, and include respectively, arms or spokes 16 and 16' provided with radial projections 17 and 17' and forward or arcuately extending arms or flanges 18 and 18'.

The outer surfaces of the arms 18 and 18' are 95 preferably concaved as shown in Figs. 3 and 4, and knife holding blocks 19 and 19' are positioned on the outer surfaces of the arms 18, the inner surfaces of the blocks 19 being convexed to con- 100 105 110

form with the concaved outer surfaces of the arms 18.

Preferably, the arms 18 and 18' are each provided with elongated slots as indicated at 20 5 through which are located knife clamping bolts 21, and the knife clamping bolts 21 also extend through the blocks 19 and 19' and through knives 22 which are supported on the blocks 19 and 19'.

The clamping bolts 21 are preferably attached 10 to the knives 22 by means of heads 23, in such a way that there can be no relative movement between the knives and the clamping bolts.

Means for arcuately adjusting the knives 22 and for preventing any backward movement of 15 the knives relative to the spiders 15 and 15', preferably includes bolts 25, each of which is screwed through one of the projections 17 or 17' and abuts against the knife holding blocks 19 and 19' respectively. A lock nut 26 is provided on 20 each bolt 25 for abutting the adjacent projection 17 or 17' to maintain the bolts 25 in proper position.

A cutter bar indicated at 27 is located transversely in the housing 12 parallel to the knife 25 mounting shaft 13, being mounted at its ends in side walls 12b and 12c. The cutter bar 27 preferably has a shearing bar 28 secured thereon which is positioned closely adjacent to the path of the rotary knives 22, for cooperating therewith to 30 shear into strips paper passing over the cutter bar.

As aforesaid, the knives 22 are circumferentially disposed and arranged with respect to the knife mounting shaft 13. The knife supporting 35 spider 15' is arcuately spaced on the shaft 13 from the spider 15, so that when the shaft is rotated in the direction of the arrow in Fig. 4, the spider 15' leads the spider 15.

Since each knife 22 is arcuate in shape and is 40 secured to each pair of knife blocks 19 and 19' respectively, of the spiders 15 and 15', the knives 22 are circumferentially and angularly disposed and arranged about the shaft 13 as an axis, and the cutting edge 29 of each knife has a leading 45 portion and a trailing portion relative to its rotation.

Means for feeding paper onto the cutter bar at right angles to the cutter bar and to the knife 50 mounting shaft, preferably includes a lower feed roll 30 keyed to a shaft 31 which is journaled in the side walls 12b and 12c of housing 12 adjacent to the cutter bar and parallel therewith. An upper feed roll 32 is keyed to a shaft 33 which is 55 journaled in the side walls of housing 12 parallel with shaft 31 and directly above the same. Preferably, the upper feed roll 32 is longitudinally slotted or corrugated as indicated at 34 for the purpose of gripping paper passing between the rolls.

Means for journaling the upper feed roll shaft 33 in the housing 12 for permitting resilient upward movement of the upper feed roll 32, may 60 include arcuate slots 36 (Fig. 2) in the side walls of the housing through which the shaft 33 extends. An arm 37 is preferably connected to each end of the shaft 33 and extends downwardly therefrom, and a tension spring indicated at 38 may be connected at one end to the lower portion of each arm 37 and at its other end to a portion 70 of the frame (not shown).

Means for conveying paper to be shredded into the feed rolls may include an articulated conveyer belt 40 which passes around a driving wheel or sprocket 41 located adjacent to the lower feed 75 roll 30. The driving wheel 41 is fixed upon a

shaft 42 which is preferably journaled in the side walls of the housing 12, as shown.

Means for driving the knife mounting shaft 13 may include a pulley 44 fixed on one end thereof and having a belt 45 thereon which is connected to a motor or other source of power (not shown).

Preferably, a fly wheel 46 is mounted on the other end of the shaft 13. Means for operatively connecting the shaft 13 to the feed rolls 30 and 32 for driving the feed rolls, preferably comprises the gearing indicated generally at 47 in Fig. 1.

The gearing 47 may include a pinion 48 fixed on the shaft 13 and meshing with a gear 49 which is rotatable on the lower feed roll shaft 31. The gear 49 is secured to or integral with a pinion 50, also rotatable on the shaft 31, and the pinion 50 meshes with a gear 51 rotatable on an idler shaft 52. The gear 51 is secured to or integral with a pinion 53 rotatable on shaft 52, which pinion 53 meshes with a gear 54 fixed on the lower feed roll shaft 31 for driving the lower feed roll 30.

Means for driving the conveyer 40 at a speed equal to the speed of the shaft 31 may include an idler gear 55 journaled on an idler shaft 56 and meshing with the gear 54. A gear 57 having the same number of teeth as gear 54 is secured on the conveyer shaft 42 and meshes with the idler gear 55, so that the shaft 42 is driven in the same direction and at the same speed as the shaft 31.

Means for driving the upper feed roll at a speed equal to the speed of the lower feed roll preferably includes a gear 58 fixed on the end of the shaft 31 opposite to the end mounting the gear 54.

The gear 58 preferably meshes with an idler 110 gear 59 which is rotatably mounted upon an idler shaft 60 on the housing 12, and the idler gear 59 meshes with a gear 61 having the same number of teeth as the gear 58. The gear 61 in turn meshes with a gear 62, having an equal number of teeth, 115 and fixedly mounted on the upper feed roll shaft 33.

Means for driving the upper feed roll shaft 33 off the lower feed roll shaft 31 while permitting limited upward movement of the shaft 33 may include the lever arm 64 which is journaled at one end on the shaft 33 and rotatably mounts the gear 61 at its other end as by the stub shaft 65. A second lever arm 66 is pivotally connected at one end to the stub shaft 65 and at the other end to 120 the idler shaft 60.

The slots 36 in which the upper feed roll shaft 33 is journaled permit upward movement of the upper feed roll against the action of spring 38, in order to take care of different thicknesses of paper stock being fed through the feed rolls. When the upper feed roll shaft 33 moves upwardly in the slots, the stub shaft 65 moves angularly downward toward the lower feed roll shaft 31, with the lever arms 64 and 66 pivoting about the stub 135 shaft 65 and the idler shaft 60, respectively, so that the gears 58, 59, 61 and 62 are maintained in driving engagement.

If it is desired to adapt the apparatus for shredding different widths of paper strips, all that is 140 necessary is to substitute for the gear 49 and driving pinion 48, a gear and pinion having the relative number of teeth required for driving the knife mounting shaft 13 and feed rolls at the desired relative speeds.

Means for outwardly deflecting paper strips or shreds successively as they are sheared from paper passing over the cutter bar, by cooperation of the shearing bar 28 and rotating knives 22, preferably includes deflecting plates or webs 70 150

which are positioned one adjacent the cutting edge 29 of each knife 22. Each deflecting plate is spaced radially inward from the adjacent knife edge, as best shown in Fig. 4 and extends substantially circumferentially from a position on the underside of the adjacent knife behind the cutting edge to a position in front of the cutting edge and spaced behind the next forward adjacent knife.

10 In other words, the rear edge 71 of each deflecting plate 70 substantially engages the underside of the adjacent knife 22 at a position spaced to the rear of the cutting edge 29 thereof, and the forward edge 72 of each deflecting web is positioned in front of the cutting edge 29 and behind the next forward knife.

15 Preferably, each web or plate 70 is mounted on the bolts 25 of the next forward knife supports 16 and 16' by means of angular ears 74 projecting from the forward edge 72 of the deflecting web and provided with apertures for fitting over the adjacent bolts 25. Nuts 75 are provided for clamping the deflecting plates or webs 70 to the bolts 25.

20 25 In the operation of the improved shredding apparatus, pack or piles 78 of paper sheets are successively positioned preferably in slightly overlapping relation as shown in Fig. 3, on the conveyor 40 and fed into the feed rolls 30 and 32.

30 Since the feed rolls are driven at equal speeds, the paper sheets are held together as they are fed through the rolls and do not become separated.

35 The resilient movable mounting of the upper feed roll 32 compensates for varying thicknesses of sheet packs so as to constantly feed the packs through the rolls without injuring the sheets thereof or separating the same, or requiring added driving power.

40 45 As the packs 78 are fed onto and over the cutter bar 27 at right angles to the rotating knives 22, the knives shear paper strips 79 from the pack each having a length equal to the full width of the pack. Since the knives are angularly arranged with respect to the cutter bar, the operation is a shearing one, each knife passing through the pack successively from its leading edge portion to its trailing edge portion, so that a minimum amount of power is required.

50 55 As the rapidly rotating knives shear the strips transversely from the sheet packs 78, the deflectors 70 successively deflect the strips outwardly as they are sheared, to prevent recutting of the same and/or winding or entangling of the strips around the various parts of the apparatus, and the strips are discharged from the apparatus by means of the discharge chute 80.

60 65 While I have shown the deflecting plates as extending a substantial distance in front of the adjacent cutting edges of the knives, this distance may be varied considerably without affecting the successful operation of the apparatus. Also, I have found that the presence of the deflecting plates is most essential at the trailing portion of the adjacent cutting edges of the knives, so that a portion of the deflecting plates adjacent the leading edge of the knife might be omitted without seriously affecting the satisfactory operation of the machine.

70 75 Moreover, while the rear edge of each deflecting plate 71 substantially abuts the underside of the adjacent knife at a position behind its cutting edge, the circumferential distance between the cutting edge of the knife and the rear edge 71 of the plate may be varied proportionately to the thickness of the paper stock

cut. That is, if the sheet packs 78 are relatively thin the rear edges 71 of the plates may be positioned relatively close to the adjacent cutting edges of the knives, and if the packs 78 are relatively thick, the rear edges 71 of the deflecting plates may be moved further behind the adjacent cutting edges.

80 85 The improved apparatus is simple and light in construction, and inexpensive to manufacture. Also, due to the fact that only one knife passes through the pack at a time, the knives may be rotated at a high speed, resulting in a relatively large capacity output.

90 The construction and arrangement of the deflecting means may be modified to a considerable extent without departing from the scope of the appended claims.

I claim:

1. Apparatus for shredding paper and the like including, a rotatable shaft, a plurality of circumferentially disposed knives mounted on the shaft and each having a cutting edge, a cutting bar cooperatively associated with said knives for shearing into strips paper passing over the cutter bar, upper and lower feed rolls adapted for feeding a pack of paper sheets onto the cutter bar at right angles to the knife mounting shaft, a substantially circumferentially disposed deflecting plate positioned adjacent to and spaced radially inward from the cutting edge of each 105 knife for deflecting the paper strips substantially radially outward, means for driving the rotatable shaft, and means operatively connecting the rotatable shaft and the feed rolls.

2. Apparatus for shredding paper and the like including, a rotatable shaft, a plurality of circumferentially arranged knives mounted on the shaft and each having a cutting edge, a cutter bar cooperatively associated with said knives for shearing into strips paper passing over the cutter bar, upper and lower feed rolls adapted for feeding a pack of paper sheets over the cutter bar at right angles to the knife mounting shaft, a deflecting plate positioned adjacent to and spaced radially inward from the cutting edge of each 120 knife, each deflecting plate extending behind the adjacent cutting edge a distance proportionate to the thickness of the pack of paper sheets, means for driving the rotatable shaft, and means operatively connected to the rotatable shaft for 125 driving the feed rolls.

3. Apparatus for shredding paper and the like including, a housing, a lower feed roll journalled in the housing, an upper feed roll parallel therewith, means on the housing journalling the upper 130 feed roll for resilient upward movement in the housing, a cutter bar mounted on the frame, a knife mounting shaft journalled in the frame parallel to the feed rolls, a plurality of circumferentially arranged knives mounted on the 135 knife mounting shaft for cooperating with said cutter bar to shear into strips paper passing through the feed rolls, means for driving the knife mounting shaft, and gearing means operatively connecting said knife mounting shaft 140 to the feed rolls for driving the feed rolls at equal speeds.

4. Apparatus for shredding paper and the like including, a rotatable shaft, a plurality of circumferentially disposed knives mounted on the 145 rotatable shaft and each having a cutting edge, a cutter bar cooperatively associated with said knives for shearing into strips paper passing over the cutter bar, and a substantially circumferentially disposed deflecting web positioned adj-

cent to and spaced radially inward from the cutting edge of each knife for deflecting the paper strips outwardly.

5. Apparatus for shredding paper and the like including, a rotatable shaft, a plurality of circumferentially arranged knives mounted on the rotatable shaft and each having a cutting edge, a cutter bar cooperatively associated with said knives for shearing into strips paper passing over the cutter bar, and a deflecting web for each knife extending substantially circumferentially from a position behind and under the cutting edge thereof to a position in front of said cutting edge and spaced behind the next forward adjacent knife.

6. Apparatus for shredding paper and the like including a rotatable shaft, a plurality of knives mounted on the shaft and each having a cutting edge, said knives being arranged circumferentially and angularly about the shaft as an axis, whereby each cutting edge has a leading portion and a trailing portion with respect to the rotation thereof, a cutter bar cooperatively associated with said knives for shearing into strips paper passing over the cutter bar, and a deflecting web positioned adjacent the trailing portion of each cutting edge and spaced radially inward therefrom.

7. In shredding apparatus including a plural-
